(57) **CLAIM**

The ornamental design for a walkie talkie as shown and described.

DESCRIPTION

FIG. 1 is a front elevational view of a walkie talkie showing the first embodiment of my new design;

FIG. 2 is a rear elevational view thereof;

FIG. 3 is a left side view thereof;

FIG. 4 is a right side view thereof;

FIG. 5 is a bottom plan view thereof;

FIG. 6 is a perspective view thereof;

FIG. 7 is a second perspective view thereof;

FIG. 8 is a third perspective view thereof;

FIG. 9 is a front elevational view of a walkie talkie showing the second embodiment of my new design;

FIG. 10 is a rear elevational view thereof;

FIG. 11 is a left side view thereof;

FIG. 12 is a right side view thereof;

FIG. 13 is a bottom plan view thereof;

FIG. 14 is a perspective view thereof;

FIG. 15 is a second perspective view thereof; and,

FIG. 16 is a third perspective view thereof.

The broken lines illustrate portions of the walkie talkie that

form no part of the claimed design.

1 Claim, 16 Drawing Sheets
